Primary Examiner — Ricky Pham(74) *Attorney, Agent, or Firm* — Kintner IP, LLC; Mary Frances Ludwig(57) **CLAIM**

The ornamental design for a spoon, as shown and described.

DESCRIPTION

FIG. 1 is a perspective view of a spoon showing my new design;

FIG. 2 is a top plan view thereof;

FIG. 3 is a left side elevation view thereof, the right side being a mirror image;

FIG. 4 is a bottom plan view thereof;

FIG. 5 is an enlarged partial sectional view along line 5-5 of FIG. 2;

FIG. 6 is a partial sectional view along line 6-6 of FIG. 2; FIG. 7 is a perspective view of the spoon shown with inset artwork wherein elements shown in broken lines form no part of the claimed design;

FIG. 8 is a perspective view of a second embodiment of the spoon;

FIG. 9 is a top plan view of the embodiment of FIG. 8;

FIG. 10 is a left side elevation view of the embodiment of FIG. 8, the right side being a mirror image; and,

FIG. 11 is a bottom plan view of the embodiment of FIG. 8. My spoon design includes a recess intended for inserting artwork.
